S. E. DAVIS

DETACHABLE POCKET

Filed May 11, 1927

UNITED STATES PATENT OFFICE.

SIMON E. DAVIS, OF SAN FRANCISCO, CALIFORNIA, ASSIGNOR TO NEUSTADTER BROS., OF SAN FRANCISCO, CALIFORNIA, A CORPORATION OF CALIFORNIA.

DETACHABLE POCKET.

Application filed May 11, 1927. Serial No. 190,459.

This invention relates to a pocket structure such as used in conjunction with wearing apparel, and especially to a detachable pocket or container to be used by carpenters and mechanics for carrying nails, etc.

It is common practice at the present time to permanently attach a pocket to the bib or apron of carpenters' overalls, which pocket serves the purpose of a receptacle for nails, etc. Pockets of this character are usually constructed of heavy fabric, such as canvas, or the like. They are fairly large as they are divided into a number of compartments to receive nails of different sizes, and as the pocket is permanently attached to the overalls, it is in the way when not required.

The object of the present invention is to generally improve and simplify the construction and operation of pockets of the character described, and especially to provide a pocket which may be readily and quickly attached to the overalls when required and detached and laid aside when other work is to be performed.

The pocket is shown, by way of illustration, in the accompanying drawings, in which—

Fig. 1 is a front view of a carpenter's overalls, showing the nail pocket applied.

Fig. 2 is a vertical cross section, taken on line 2—2 of Fig. 1.

Fig. 3 is an enlarged section, taken on line 3—3 of Fig. 1, showing the snap buttons whereby the detachable pocket is secured.

For the purpose of illustration, ordinary overalls are shown, in which A indicates the leg portions; B the body portion; C the bib or apron portion; and D the straps or suspenders, whereby the bib is supported with relation to the shoulders. The nail pocket illustrated in the present instance is generally indicated at E. Any standard type of nail pocket structure may be employed; that is, a pocket or container which may be divided into a number of compartments, such as indicated at 2, 3, 4, 5, etc., so as to permit segregation of nails of various sizes.

The pocket illustrated is in this instance shown as provided with an upper strip or extension 7. The strip or upper extension 7 serves the function of supporting the weight of the pocket, and it also serves the purpose of supporting the main securing means, to-wit, snap buttons of the character illustrated at 9 (see Figs. 1 and 3).

The bib or apron C is in this instance shown as attached to the body portion by a line of sewing or the like, as indicated at 10. A flap or overhanging portion 11 is formed, and the upper extension 7 of the pocket is introduced between the body portion B and the overhanging flap 11. The snap buttons 9 are then applied and the pocket as a whole is thus rigidly supported and secured; that is, the entire weight of the pocket and its contents is supported by the snap buttons 9, and displacement of the pocket is prevented.

The flap 11 serves two main functions: first, that of permitting the use of double snap buttons, the outer snap buttons 9 carried by the flap 11 and the inner snap buttons 12 which are secured in the body portion. The flap also serves the function of forming a guide so that when the wearer of the overalls slips his hand downwardly over the bib, the flap 11 guides the hand directly into one or another of the compartments of the pocket. On the other hand, if the flap was eliminated the wearer of the overalls might have a tendency to insert his hand between the upper edge of the pocket and the body.

While certain features of the present invention are more or less specifically illustrated such, for instance, as employing snap buttons for the purpose of securing the pocket to the bib or body portion of the overalls, it is obvious that other fastening means may be employed.

I also wish it understood that the materials and finish of the several parts employed may be such as the experience and judgment of the manufacturer may dictate or varying conditions may demand.

Having thus described my invention, what

I claim and desire to secure by Letters Patent is—

In a garment of the character described, a body portion, an apron secured to the body portion and provided with a free overhanging flap, a pocket having an upper extension formed thereon insertable between the body

portion of the garment and the apron flap, snap buttons securing the upper extension of the pocket to the body portion of the garment at a point underneath the flap, and snap buttons carried by the flap to secure the flap on top of the pocket extension. ¹⁰
